VALVE SEAT

Charles R. Suska, Corry, Pa., assignor to Aero Supply Mfg. Co., Inc., Corry, Pa.

Application November 4, 1948, Serial No. 58,200

1 Claim. (Cl. 251—167)

1

This invention relates to a valve seat, and has as its primary object an improved valve seat which may be readily removed and replaced with a minimum of effort and difficulty.

A further object of the invention is the provision of such a valve seat which includes a resilient cylindrical member and a split ring or band for holding the member in position interiorly of the valve body.

To the foregoing objects, and others which may hereinafter more fully appear, the invention consists of the novel construction, combination and arrangement of parts, as will be more specifically referred to and illustrated in the accompanying drawing, but it is to be understood that changes, variations, and modifications may be resorted to which fall within the scope of the invention as claimed.

The single figure of the drawing is a fragmentary vertical section of one form of float valve embodying the improved valve seat of the instant invention.

Referring to the drawing, the numeral 15 designates generally a valve body which is formed of a boss 16 having an annular flange 17 and an annulus 18 secured to and supported above the flange 17 by means of spaced connecting webs 19. The spaces between the webs 19 form fluid outlet passages whereby the fluid passing through the bore 21 of the boss 16 will be discharged into a tank within which the valve structure is mounted. The body 15 also includes at its inner end a boss 22 which is formed with a bore 23 substantially larger than the threaded bore 21 and the lower portion of the bore 23 terminates in a transversely arcuate groove 24. The bore 23 forms a shoulder 25 constituting a seat on which a resilient ring-shaped valve seat member 26 is adapted to engage. The valve seat member 26 extends slightly above the top or inner end of the boss 22 so that the diaphragm carried valve member may engage the upper or inner end of the seat 26. The valve seat member 26 is fixed within the bore 23 and the groove 24 by means of a split clamping band or ring 27 which engages the inner face of the seat member 26 and is formed with a bead 28 within the concave inner side of which a locking ring 29 is adapted to engage.

The body 15 has secured to the upper or inner end thereof a cap generally designated as 30, the cap 30 being secured to the annulus 18 by fastening members 31. A flexible diaphragm 32 is secured between the marginal portion of the cap 30 and the annulus 18 and extends over the valve seat member 26. The diaphragm 32 forms a

2

pressure chamber 33 between the upper side of the diaphragm and the inner side of the cap 30, the purpose for which will be hereinafter described. The diaphragm has secured to the lower side thereof a valve plate 34 which is formed with a downturned or curved marginal edge 35 and a second clamping plate 36 is secured to the upper or inner side of the diaphragm 32. The two plates 34 and 36 are held in clamping position by means of a bushing generally designated as 37 which extends through the center of the two plates 34 and 36 and the diaphragm 32. The bushing 37 includes a substantially cylindrical body 38 having a lower flange 39 bearing against the lower side of the valve plate 34. The bushing 37 also includes a reduced diameter nipple 40 extending into the pressure chamber 33 which is formed with an inner or top wall 41 and also with a passage 42 which communicates the bore 43 of the nipple with the pressure chamber 33. The inner portion of the bushing 37 is crimped or turned over as indicated at 44 so as to tightly secure the plates 34 and 36 on opposite sides of the diaphragm 32.

The plates 34 and 36 are also formed outwardly of the bushing 37 with annular beads 45 and 46, respectively, which form additional clamping or locking means for tightly holding the diaphragm 32 between the two plates 34 and 36. The lower or outer end of the bushing 37 has extending thereacross a screen 47 and a cap 48 formed with apertures 49 engages over the screen 47, being clamped on an annular bead 50 formed on the bushing 37 by means of a split clamping ring 51. In order to assist in the movement of the diaphragm 32 to closed position where the valve plate 34 will engage the valve seat 26, a spring 52 is interposed between the plate 36 and an upwardly offset central portion 53 formed in the cap 30. The cap 30 has formed therewith a boss 54 within which a bushing 55 is threaded.

The bushing 55 is provided at its lower or outer end with a needle valve seat 56 and at its upper or inner end with a second needle valve seat 57. The cap 30 has extending upwardly therefrom on opposite sides of the boss 54 a pair of upstanding ears 58 and the bushing 55 is locked against rotation by means of a locking wire 59 extending through the bushing 55 and through at least one ear 58.

A pressure release needle valve 60 is loosely disposed within the bushing 55 and is formed with a lower valve head 61 adapted to engage the seat 56 and is also formed with an upper valve head 62 engageable with the valve seat 57.

The needle valve member 60 includes a stem 63 extending upwardly from the valve head 62 and the stem 63 is formed with an annular groove 64 within which the slotted portion 65 of a float lever 66 is adapted to loosely engage. The float lever 66 is rockably mounted on a pivot pin 67 extending through the ears 58 and the lever 66 has secured to its inner end a hollow metal float body 68, the body 68 being secured to the lever 66 by fastening means 69. The float 68 is formed of a pair of telescoping body members 70 and 71 which are soldered or otherwise fixedly secured together so as to provide a sealed buoyant float member.

A hood or shield 72 is secured about the float 68 and is formed with a plurality of openings 75 so that fluid may freely enter the interior of the shield or hood 72 and activate or move the float 68. The valve structure hereinbefore described may be used either in an upright position, or if desired, this structure may be inverted. When the valve structure is in an upright position the valve head 61 is not used and is held against engagement with the seat 56 at the time the float lever 66 is rocked downwardly by lowering of the fluid level in the tank through the medium of a stop pin 73 which extends through the two ears 58. When the valve structure is inverted, valve head 62 is not used and the pin 73 is positioned in a second opening 74 formed through the ears 58 at a point confronting the relatively large pair of openings 75 in the hood 72 so that the pin 73 may be interchanged in either one of the openings provided for that purpose without removing the hood.

In the use and operation of this valve structure the valve body 15 may as herein disclosed be mounted in upright position with the boss 16 threaded onto the end of a fluid pressure supply source and mounted within a fluid tank. With the valve structure 15 in an upright position and assuming that the liquid level is below the predetermined quantity, float 68 will swing downwardly, moving therewith needle valve operating lever 66 and lowering valve head 62 to open position with respect to the valve seat 57. Pressure chamber 33 will thereupon be open to the interior of the guard or hood 72 so that the incoming fluid will move valve member 34 and diaphragm 32 upwardly to open position. The incoming fluid will flow outwardly through the spaces 20 into the main tank associated with this valve structure. At the same time that fluid is flowing through the valve seat member 26 and the passages 20 a small quantity of this fluid will pass through bushing 37 and opening 42 into the pressure chamber 33. However, as pressure chamber 33 is at this time open by reason of needle valve 60 being in open position, the fluid entering chamber 33 will flow out into the shield or guard 72 and into the main tank. As the liquid level in the tank rises float 68 will be moved upwardly and when this float is moved upwardly to a point where needle valve 60 is in closed or restricted position with respect to seat 57, pressure in chamber 33 will be built up in this chamber due to the fact that the

fluid outlet is either closed or smaller than the fluid inlet. When sufficient pressure force has been built up in pressure chamber 33 to overcome the pressure force of the incoming fluid, diaphragm 32 will move valve plate member 34 downwardly to engaging position with respect to valve seat member 26 and thereby cut off the flow of incoming fluid. The provision of the apertured hood or guard 72 eliminates the surging of fluid in the tank from unduly affecting the position of float 68. This valve structure has been designed particularly for use in fuel tanks of airplanes and especially the main fuel tank where the fuel is discharged from the auxiliary tanks.

In practice when valve plug 60 is moving to closed position the rate of exhaust of fluid from pressure chamber 33 will be less than the rate of fluid entering chamber 33 so that pressure will build up in chamber 33 until the pressure force in this chamber overcomes the force of fluid against the lower side of diaphragm. When pressure force in chamber 33 is greater than the pressure force on the lower side of the diaphragm the latter will move downwardly to closed position. The pressure required to close diaphragm 32 may be built up in chamber 33 before valve 60 is completely closed.

I claim:

30 A valve seat for a float valve structure comprising a body having a through passage and an annular groove adjacent one end of said passage said valve seat comprising, a resilient cylindrical valve seat member disposed in said passage and projecting from said one end, a split cylindrical band bearing against the inner side of said seat member and formed with a bead engaging in said seat member whereby to press said seat member outwardly into said groove, said band having substantial width and reinforcing said seat member against distortion, said bead having a concave inner side, and a resilient split locking ring engaging in the concave inner side of said bead whereby to lock said band and seat member relative to said passage.
